Attorney.

UNITED STATES PATENT OFFICE.

THEODOR ZANGER, OF BUFFALO, NEW YORK, ASSIGNOR TO WATSON E. KING AND CHARLES D. WHITTET, BOTH OF SAME PLACE.

VELOCIPED.

SPECIFICATION forming part of Letters Patent No. 352,503, dated November 9, 1886.

Application filed June 23, 1886. Serial No. 205,953. (No model.)

To all whom it may concern:

Be it known that I, THEODOR ZANGER, of Buffalo, in the county of Erie and State of New York, have invented certain new and useful Improvements on Velocipedes; and I do hereby declare that the following description of my said invention, taken in connection with the accompanying sheet of drawings, forms a full, clear, and exact specification, which will enable others skilled in the art to which it appertains to make and use the same.

My present invention has general reference to improvements in bicycles, tricycles, and similar vehicles propelled by a pedal movement; and it consists, essentially, in the novel and peculiar combination of parts and details of construction, as hereinafter first fully set forth and described, and then pointed out in the claims.

In the drawings already mentioned, which serve to illustrate my said invention more fully, Figure 1 is a side elevation of a tricycle constructed in accordance with my invention. Fig. 2 is a plan of the same, portion of the seat being broken away to expose underlying parts. Fig. 3 is a plan of the connecting-rod and pedal-lever on an enlarged scale.

Like parts are designated by corresponding letters of reference in all the figures.

The object of my present invention is the production of a cheap and serviceable tricycle and similar vehicle. To attain this end I construct the same, essentially, of a frame, A A', consisting of two bars of iron, pieces of gas-

pipe or similar metallic parts, bent into the shape shown in Figs. 1 and 2, the forward ends of these pieces being securely fastened in sockets B B', formed in one piece with the head C in the process of casting in malleable iron or other suitable metal. The side pieces, A A', are on their rear end fastened in sockets D, having cast integrally boxes E, forming journals for the double-cranked axle F, as clearly illustrated in Fig. 2.

About midway between the head C and the journal-sockets D there is provided a cross-piece, G, for the purpose of strongly bracing the frame. The head C has rearwardly extending an arm or bracket, H, to which are

pivoted two pendulum arms or levers, I I', 50 said levers being connected with the cranks of the axle F by means of two connecting-rods, J J', so as to communicate motion to the crank-shaft in a manner hereinafter to be more particularly referred to. The forward end of 55 the connecting-rods J terminates in a circular head, j, having in its face a circle of serrations or projections, i, Fig. 3. With this head j engages the pedal-arm K, which has a head, k, corresponding with the head j and secured 60 thereto by a central bolt, a, in such manner that the two serrated circles engage each other, and thereby securely hold the pedal-arm K in any desired position. The rear portion of the connecting-rod J is slotted at b and terminates 65 in a journal, L, having two lugs, l l, provided with a screw-bolt, d, to draw the journal together. The connecting-rods J are produced in the process of casting in malleable metal, 70 and the object of constructing the journal L on the forked end b is to provide for ready means of fitting the parts with capability of making adjustment caused by wear and yet form the parts of the journal in such a way that no part of it can be lost during travel. 75

To the pedal-arms K are swiveled the pedals N in a manner well known, so as not to require extended description.

One of the wheels W is securely affixed to the axle F, but the other revolves on the same, 80 thereby enabling the vehicle being readily guided and steered by the operator in conjunction with a steering-wheel, P, revolving between the arms of a fork, f, the shank g of which operates within the head C in the usual 85 manner. To the upper end of this shank is secured an eye-piece, Q, to which the hand-rod R, with its handle S, is swiveled at T.

U is the seat, and V the back.

It will be readily observed that one of the 90 essential features of my present construction is the peculiar location and arrangement of the pendulum-levers as suspended from the arm H, formed in one piece with the head C. This construction enables the pedals to work 95 in nearly a straight line, (the arc described by said pedal being but a slight curve.) This is a desirable feature in vehicles propelled by

ladies and children, for obvious reasons. Another very essential element in the construction of my tricycle is the adjustable pedals, whereby by turning the arms K forward or backward they can be readily adapted for children of different ages or size.

Having thus fully described my invention, I claim as new and desire to secure by Letters Patent of the United States—

- 10 1. In tricycles and similar vehicles, a head, C, having a rearwardly-projecting arm to which are pivoted two pendulum-levers, K K', connecting-rods J J', and the double-cranked axle F, the whole being constructed and arranged to operate substantially as and for the object specified.
- 15 2. In pedal mechanism, the connecting-rod J, having on its forward end a head, j, provided with a circular serrated portion, i, and
- 20 the pedal-arm K, having a circular head provided with serrations matching those of the head j, the two heads being secured together by a bolt, a, as and for the object described.

3. In pedal mechanism for tricycles, the connecting-rod J, having a circular head provided with serrations, as described, the pedal-arm K, having a serrated head engaging said head j, and the pedal N, said heads being adjustably affixed together by means of a bolt, a, forming the pitman for connecting said connecting-rod with the pendulum-lever I, as stated.

4. In velocipedes, the connecting-rod J, having on its rear end a fork, L, secured together by a bolt, d, said fork having a journal-bearing for the crank-axle and being adapted for springing over the crank-pins, substantially as and for the purpose stated.

In testimony that I claim the foregoing as my invention I have hereto set my hand in the presence of two subscribing witnesses.

THEODOR ZANGER.
